(57) **CLAIM**

The ornamental design for a storage chest with a lid storage compartment, as shown and described.

DESCRIPTION

FIG. 1 is a perspective front view of a storage chest with a lid storage compartment with the lid shown in an open position in accordance with the present invention;

FIG. 2 is a front view of the storage chest of FIG. 1;

FIG. 3 is a rear view of the storage chest of FIG. 1;

FIG. 4 is a left side view of the storage chest of FIG. 1;

FIG. 5 is a right side view of the storage chest of FIG. 1;

FIG. 6 is a top view of the storage chest of FIG. 1; and,

FIG. 7 is a bottom view of the storage chest of FIG. 1.

The broken lines in the Figures depict portions of the storage chest that form NO part of the claimed design.
